UNITED STATES PATENT OFFICE.

MERRILL E. CLARK, OF NEW YORK, N. Y.

AEROPLANE.

1,140,444.

Specification of Letters Patent. Patented May 25, 1915.

Application filed August 5, 1912. Serial No. 718,240.

To all whom it may concern:

Be it known that I, MERRILL E. CLARK, a citizen of the United States, residing at New York, in the county and State of New York, have made a new and useful Improvement in Aeroplanes, of which the following is a specification accompanied by drawings, forming a part of the same.

The objects of my present invention are, to provide means for varying the axis of the propeller, to provide means for applying a direct lifting force to the machine independently of the motors, to provide yielding or cushioning means for resisting the impact of the machine in alighting, and to provide an improved stabilizer, and I accomplish these results by means of the construction and arrangement of parts as hereinafter described, the novel features being pointed out in the annexed claims.

Referring to the accompanying drawings, Figure 1 represents a side view of an aeroplane embodying my invention. Fig. 2 is a plan view. Fig. 3 is a side view of a portion of the machine showing the propeller blades held in a horizontal plane of rotation. Fig. 4 is a sectional view of my improved stabilizer and connected operative mechanism, the stabilizer being shown in a collapsed condition. Fig. 5 represents the stabilizer in sectional view and in its extended or operative position. Fig. 6 represents the mechanism for applying a lifting force to the aeroplane, shown in sectional view. Fig. 7 represents a central sectional view of the air valve for controlling the compressed air by which the lifting apparatus is actuated, and also by which the stabilizer is expanded or collapsed. Fig. 8 is a side view of the machine with the stabilizer extended. Fig. 9 is a top view of the collapsible framework of the stabilizer, and Fig. 10 is a detached plan view of the cross bars of the stabilizer.

Similar letters and figures of reference refer to similar parts in the different views.

The accompanying drawings represent, for the purpose of illustrating the character of my present invention, that class of aeroplanes known as a biplane, in which 1 is the upper plane and 2 the lower plane. Mounted upon the framework of the machine is the usual alighting gear and tail, or other guiding means, which may be of any suitable form of construction. Supported upon the framework is a motor 3 connected by gears 4 with propeller shafts 5, 5, journaled in a

framework 6 capable of swinging loosely about a motor shaft 7.

In Fig. 1 the propeller shafts 5 are represented in a horizontal position, bringing their propeller blades 8 in position to force the machine horizontally forward. Connected with the framework 6 in which the propeller shafts are journaled, is an arm 9 connected by a link 10 with a hand lever 11, by which the frame carrying the propeller shafts may be swung around the axis of the motor shaft 7 to bring the blades 8 into a horizontal plane beneath the lower plane 2. In this position the revolution of the propellers will impart an upward or lifting force to the machine. The machine is provided with a tank 12 which is charged with compressed air to be used for the purpose of actuating the lifting and stabilizing mechanisms as hereinafter described.

Supported in the framework is a compressed air cylinder 13, shown on a larger scale in sectional view in Fig. 6. The cylinder 13 is closed at both ends and is equipped with a piston 14 having a piston rod 15 extending through the lower closed end of the cylinder, and carrying at its lower end a spider 16 comprising arms upon which are mounted the rollers 17. Communicating with the upper end of the cylinder 13 is a pipe 18, and communicating with the lower end of the cylinder 13 is a pipe 19. The pipe 18 has a valve controlled connection with a pipe 20 which leads to the compressed air tank 12. By means of a rotating valve 21 which may be operated by a handle 22 or in any convenient manner, compressed air is admitted through the pipe 18 above the piston 14.

In the normal position of the apparatus the piston 14 is at the upper end of the cylinder 13 holding the spider 16 and rollers 17 in their elevated position and allowing the machine to be supported upon a running gear comprising the rolls 23, 23.

In beginning a flight, with the propeller blades 8 in the position shown in Fig. 3, the machine is not only lifted by the rotation of the blades, but a lifting force is applied independently of the motor by admitting compressed air into the cylinder 13 above the piston 14. Any air existing in the cylinder 13 below the piston 14 will be forced out through the pipe 19 and to the outer air through a communicating passage in the valve 21. By this means a sudden down-

ward impulse is given to the piston which reacts to force the machine upward. The construction of the valve 21 is illustrated in Fig. 7. It consists of a rotating spindle 24 having a portion cut away at 25 to form a connecting passage between the pipes 18 and 20 when the valve is in the position shown in Fig. 7. In this position air escapes from the lower end of the cylinder 13 through a passage 26 into a chamber 27 which is open at one end of the spindle 24. By rotating the spindle 24 the pipes 19 and 20 may be connected by the passage 25, the passage 26 closed, and the passage 28 brought into alignment with the pipe 18. When the spider 16 has been forced downward as above described, a charge of compressed air may be maintained above the piston 14, forming an air cushion for the piston 14 as the rollers 17 are brought into contact with the earth by the downward movement of the machine.

In the event of any accident to the machine, such, for example, as would result in the cessation of the motor, causing the machine to be precipitated by gravity, I provide a stabilizer or mechanism by which the planes in their downward flight will be maintained by the action of the atmosphere in proper position to cause the machine to glide forward, and thereby maintain to a certain extent the buoyancy which would be produced by the rotation of the propeller blades.

My improved stabilizer consists broadly in providing means for erecting above the planes of the machine, guiding means which will enable the resistance of the atmosphere to offset any tendency of the machine to rotate in any direction about a horizontal axis, thereby maintaining the machine in an upright position. I accomplish this result by providing the machine with a compressed air cylinder 29 having a hinged connection at 30 with the upper plane 1. The lower end of the cylinder 29 terminates in a bar 31 connected by a link 32 with a hand lever 33, provided with any usual well known locking mechanism by which it may be locked in any desired position.

The lower end of the cylinder 29 is capable of a sliding movement forward or backward in ways 34 mounted on the framework of the machine. By means of the lever handle 33 a forward or rearward sliding movement may be imparted to the lower end of the cylinder 29 in the ways 34, by which the cylinder 29 is rocked on its pivotal connection 30, and its angle to the plane 1 varied as desired.

The cylinder 29, which is shown in sectional view and on a larger scale in Fig. 4, incloses a telescopic cylinder 35 having a packing 36 at its lower end in sliding contact with the interior of the cylinder 29.

The telescopic cylinder 35 also slides in contact with a packing 37 at the upper end of the cylinder 29. Sliding within the telescopic cylinder 35 is a piston 38 having a piston rod 39 extending through a head 40 at the upper end of the cylinder 35, and connected at its upper end to the stabilizing vanes as hereinafter described. The piston rod 39 passes loosely through a hub 41 and is connected at its upper end to a head 42. Extending radially from the hub 41 and rigidly attached thereto are the four equidistant arms 43. Pivots connected to the head 42 are four tubes 44, and pivotally connected to the upper end of the cylinder 29 are four tubes 45. The tubes 44 and 45 correspond to the four radial arm 43. To the outer ends of each of the radial arms 43 are pivoted rods 46 and 47. The rods 46 telescope into the tubes 44 and the rods 47 telescope into the tubes 45. Attached to the tubes 44 and 45 and also to the radial arms 43 are silk or canvas vanes 48 which are held in an extended and taut position when the framework connected with the piston rod 39 is held in its extended position, as represented in Fig. 5.

In the normal position of the stabilizer, as shown in Fig. 4, the piston 38 is at the lower end of the telescopic cylinder 35, and the cylinder 35 is wholly inclosed within the cylinder 29. When in this position the head 42 will be drawn downward, bringing the hub 41 against the head 40, as shown in Fig. 4. In this position of the head 42 the rods 46 will be pushed into the tubes 44 and the rods 47 will be pushed into the tubes 45 and the entire framework will rest in a collapsed position above the upper plane 1.

Leading from the compressed air tank 12 is a pipe 49 having a valve controlled communication with the pipes 50 and 51 leading to the lower and upper ends respectively of the cylinder 29. The valve 52 by which the passage from the compressed air tank to the cylinder 29 is controlled, is a duplicate of the valve 21 illustrated in sectional view in Fig. 7. The valve 52 is provided with a radial arm 53 connected by a link 54 with a bell crank 55 which is connected by a link 56 with a foot lever 57 pivotally supported in a convenient position to be reached by the foot of the aviator.

When the stabilizer is in its normal or collapsed position, as shown in Fig. 4, the valve 120 52 is operated to admit compressed air through the pipe 50 into the lower end of the cylinder 29, causing the telescopic cylinder 35 and piston 38 to be moved upwardly. The cylinder 35 is moved until interrupted by the stops 58 in the cylinder 29, the piston 38 continuing its movement until stopped by the head 40. The overlapping of the cylinders 29 and 35 which is secured by the stops 58 serves to hold the two cylinders 125 130

ders in rigid relation to each other. The upward movement of the piston 38 carries the head 42 to its highest position expanding the telescopic framework, and holding the silk 5 or canvas vanes in a taut position and in planes at right angles to each other. A reversal of the valve 52 admits compressed air through the pipe 51 to the upper end of the cylinder 29 forcing the telescopic cylinder 35 10 downward to its lowest point at which it admits compressed air through an opening to the interior of the cylinder and above the piston 38, causing the latter to be forced downward and bringing the telescopic framework into its collapsed position, as shown in Fig. 4. When the stabilizer is in 15 its operative position, as shown in Fig. 5, its axis may be brought into a true vertical position relative to the planes of the machine 20 by the movement of its lower end in the ways 34 and locked in any desired position by any suitable locking mechanism connected with the lever handle 33.

I claim,

- 25 1. In an apparatus of the kind specified, a framework, a series of vanes mounted in intersecting planes, means for supporting the vanes above the framework, and means for varying the elevation of the vanes in a line 20 coincident with their axis of intersection.
- 20 2. In an apparatus of the kind specified, a series of vanes located in intersecting planes having substantially a vertical axis of intersection, and means for lowering said vanes

in a line coincident with their axis of intersection. 35

3. In an apparatus of the kind specified, a framework, a stabilizing device above said framework, comprising a series of vanes in intersecting planes with substantially a vertical axis of intersection, means for raising and lowering said vanes in a line coincident with their axis of intersection, and means 40 for collapsing said vanes by their downward movement and expanding them by 45 their upward movement.

4. In an apparatus of the kind specified, a stabilizer disposed above the framework of the apparatus, and means for raising and lowering said stabilizer, comprising a double 50 acting cylinder, a second cylinder telescopically mounted within said first cylinder, and a piston within said second cylinder having an operative connection with the stabilizer, and means for admitting a fluid under pressure 55 above and below said piston at will.

5. In an apparatus of the kind specified, a piston equipped cylinder hinged at its upper end to the framework of the machine, a stabilizer supported upon the piston rod and 60 comprising a series of vanes mounted in intersecting planes, and means for moving said cylinder on its hinged connection.
